Primary Examiner — Robert M Spear*Assistant Examiner* — Marissa J Cash(74) *Attorney, Agent, or Firm* — Thomas B. Ryan; Harter Secrest & Emery LLP**CLAIM**

I claim the ornamental design for a cap, as shown and described.

DESCRIPTION

FIG. 1 is a top front perspective view of a cap in accordance with a first embodiment of this invention.

FIG. 2 is a front elevation thereof, the rear elevation and left and right side views being identical therewith.

FIG. 3 is a top front perspective view of a cap in accordance with a second embodiment of this invention.

FIG. 4 is a front elevation thereof, the rear elevation and left and right side views being identical therewith.

FIG. 5 is a top front perspective view of a cap in accordance with a third embodiment of this invention.

FIG. 6 is a front elevation thereof, the rear elevation and left and right side views being identical therewith.

FIG. 7 is a top front perspective view of a cap in accordance with a fourth embodiment of this invention; and,

FIG. 8 is a front elevation thereof, the rear elevation and left and right side views being identical therewith.

The broken lines are included for the purpose of illustrating structural environment and form no part of the claimed design.
